UNITED STATES PATENT OFFICE

EUGENE A. LEARY, OF CINCINNATI, OHIO

SUPPORT STRUCTURE

Application filed January 20, 1932. Serial No. 587,645.

This invention relates to a foldable or collapsible support structure.

An object of the invention is to provide such a device formed of separable members adapted to be interlocked in operative position to preclude collapsing of the device.

Another object is to provide such means adapted to serve as an undersupport and also as a supporting medium upon which to suspend objects.

Another object is to provide integral means in a device of the class described for assuring a rigid operative position of the device.

Another object is to provide a supporting structure simple in use and inexpensive in manufacture.

These and other objects are attained by the means described herein and illustrated in the accompanying drawing, in which:

Fig. 1 is a side elevational view of a device of the present invention operatively positioned and with an object suspended thereon.

Fig. 2 is a view taken on the line 2—2 of Fig. 1.

Fig. 3 is a view of one of the leg members of the invention shown in folded position.

Fig. 4 is an enlarged view taken on the line 4—4 of Fig. 3 with parts broken away.

Fig. 5 is a perspective view of the support beam of the present invention.

The support structure of this invention is adapted to fill the need for such means which are absolute proof against collapsing when in operative position. The device therefore is particularly adapted for use, for example, as a means for suspending a child's cradle, hammock, or the like, since the danger of collapse is entirely obviated by the means of this invention. Moreover the usual collapsible hinges, brackets, etc., commonly found on devices of this kind and which are undesirable because of the ready possibility of the fingers or clothing being caught therein, are substantially obviated by the means of this invention.

The support structure herein set forth is likewise constructed with a view to rendering it firm and stable in operative position with practically no danger of its being upset or overbalanced. It is obvious that these means are adapted for innumerable uses other than the ones suggested.

The device comprises a pair of leg members 8 and 9 adapted to support and be interlocked with a support beam 10. Each leg member comprises two elongated complementary sections 11 and 12. Both sections 11 and 12 are formed at their top ends with lateral extensions 13 and 14, extension 13 being of greater transverse width than section 14. The vertical edge of extension 13 is provided with a dovetail notch 15. The similar edge of extension 14 is plain and is hinged to the edge of extension 13 by suitable hinges 16 secured one on each side of the notch 15. A pair of opposed holes 17 is provided one each in the edges of extensions 13 and 14 (Fig. 4). A suitable hook 18 may be fastened upon the outer face of the extension 13 and a suitable receiving ring 19 for the hook may be secured upon the outer face of the extension 14. The two sections thus joined are adapted to be hingedly moved into operative position clearly seen in Fig. 2 and in which position the opposed edges of extensions 13 and 14 are locked in abutment with one another by means of the hook 18. The two sections forming each leg member are preferably downwardly divergent relative to one another so that said leg members are adapted for firm operative positioning to resist upsetting or tipping movement.

The support beam 10 consists of a single straight member of substantial size having its ends similarly cut to provide the abutments 20 projecting laterally at each end of the beam and the dovetailed extension 21 at each end of the beam. A stud 22 projects laterally of each extension 21.

For associating the support beam 10 with

the leg members, the latter are hingedly moved to the position shown in Fig. 3 so as to permit access to the notches 15. Said notches are of such size and formation as to snugly receive the extensions 21 of the support beam. After such positioning of the extensions 21, the section 12 of each leg member is hingedly swung into operative position against the exposed side of the extension 21. It will be seen in Fig. 2 that the greater transverse width of the extension 13 makes it possible that the notch 15, in the operative position of the leg members, is disposed in the central vertical line of the leg members. At this time the studs 22 are seated in the holes 17 for assuring a rigid positioning of the beam. The placing of the hook 18 into its receiving ring 19 locks the support structure in operative position. It will be seen in Figs. 1 and 2 that the outermost edges of the abutments 20 are so cut as to provide supporting surfaces 23 which lie flush against the inner face of the extension 13 of each leg member in operative position whereby the whole device is further fortified against loose frictional movement in operative position.

As illustrated in Fig. 1, a number of rings 24 may be provided on the under edge of the beam 10 and upon which rings a child's cradle or other object may be suspended. It will be seen clearly in Fig. 2 that the suspended object is disposed in the central vertical line of the support structure so that danger of upsetting is rendered negligible. It is likewise obvious that the device may be taken apart and stored away in a comparatively small space when not in use and, as above suggested, that its uses are various.

What is claimed is:

- 40 1. A foldable support structure consisting of a pair of leg members each comprising two sections provided at the top with lateral opposed extensions hingedly joined for edge-wise abutment in operative position, one of said extensions being wider than the opposed extension and provided in its edge with a dovetail notch disposed in the central vertical line of the operatively positioned leg member, a support beam having dovetailed ends snugly receivable in said notches and adapted to be locked therein upon movement of said sections into edge-wise abutment, enlarged portions on opposite sides of the beam adjacent said ends and provided with supporting surfaces adapted upon positioning of the beam to abut the inner face of the notched extension adjacent thereto, and means for releasably clamping the leg members in operative relationship.
- 50 2. A foldable support structure consisting of a pair of leg members each comprising two sections hingedly joined for lateral edge-wise abutment in operative position, a dovetail notch being provided in the abutting edge of one of said sections in each leg member adja-

cent the top thereof, a support beam having dovetailed ends snugly receivable in said notches and adapted to be locked therein upon movement of said sections into edge-wise abutment, enlarged portions on the beam adjacent said ends and adapted to abut the inner sides of the leg members upon positioning of the beam, and means for releasably clamping the leg members in operative relationship.

In testimony whereof, I have hereunto subscribed my name this 18th day of January, 1932.

EUGENE A. LEARY.
